UNITED STATES PATENT OFFICE

133,985

DESIGN FOR A CUTTING IMPLEMENT SHEATH

Frederick Ehrsam, Reading, Pa.

Application September 29, 1941, Serial No. 103,556

Term of patent 3½ years

To all whom it may concern:

Be it known that I, Frederick Ehrsam, a citizen of the United States of America, residing at Reading, in the county of Berks and State of Pennsylvania, have invented a new, original, and ornamental Design for a Cutting Implement Sheath, of which the following is a specification, reference being had to the accompanying drawings forming part thereof.

Figure 1 is a perspective view of a cutting implement sheath embodying my new design, and shows the same as it appears when open to receive the implement.

Fig. 2 is a front elevational view thereof, as it appears when closed.

Fig. 3 is a rear elevational view thereof.

Fig. 4 is a side elevational view thereof, as seen from the left of Fig. 2, but on a somewhat larger scale than Fig. 2.

Fig. 5 is a side elevational view thereof, on the same scale as Fig. 4, and shows the sheath as seen from the right of Fig. 2.

I claim:

The ornamental design for a cutting implement sheath, as shown.

FREDERICK EHRSAM.
